United States Patent

Des. 234,310
Patented Feb. 11, 1975

234,310

PENDANT

Ernest Camerino, 1310 NW. 43rd Ave.,
Fort Lauderdale, Fla. 33313

Filed May 7, 1973, Ser. No. 358,043

Term of patent 7 years

Int. Cl. D11—01

U.S. Cl. D45—16 A

FIG. 1.

FIG. 2.

FIG. 1 is a front elevational view of a pendant embodying my new design, and

FIG. 2 is a side elevational view of the same.

The back face of the pendant is flat and unornamented.
I claim:

The ornamental design for a pendant, as shown and described.
